UNITED STATES PATENT OFFICE.

JAMES WRIGHT MACFARLANE, OF GLASGOW, SCOTLAND.

SPEED-GOVERNOR.

SPECIFICATION forming part of Letters Patent No. 755,575, dated March 22, 1904.

Original application filed May 27, 1901, Serial No. 62,110. Divided and this application filed February 5, 1903. Serial No. 142,083. (No model.)

To all whom it may concern:

Be it known that I, JAMES WRIGHT MACFARLANE, a subject of the King of Great Britain, and a resident of Glasgow, Scotland, have 5 invented certain new and useful Improvements in Speed-Governors, of which the following is a specification.

This invention relates to speed-governors; and it has for its object to provide an improved 10 governor or regulator of the class shown in my copending application, filed May 27, 1901, Serial No. 62,110, of which this application is a division.

The invention consists of the parts and the 15 combinations of parts more fully hereinafter described, and pointed out in the claims.

In the drawings forming a part of this specification, Figure 1 is a section through the casing which usually surrounds the water-wheel, said wheel being shown by means of a 20 full-line circle and a dotted-line circle, with one embodiment of my invention mounted within the casing. Fig. 2 is another embodiment of my invention, illustrated similarly to Fig. 1. 25 Fig. 3 is still further embodiment of my invention. Fig. 4 is a still further embodiment of my invention.

The casing A has mounted therein a wheel B, which rotates in the direction of the arrow 30 D. The motive power of the wheel is a fluid delivered to the bucket through a nozzle E tangentially and in a line central to the periphery of the wheel. In starting, the fluid strikes the wheel, and the escaping or spent fluid is immediately thrown backward. As the speed 35 of the wheel increases this backward motion of the escaping or spent fluid becomes less until the correct speed is reached, when the fluid merely drops free of the wheel without 40 backward motion. If, however, the speed of the wheel becomes greater than the correct speed, the escaping fluid has a forward motion in the direction of the rotation of the wheel.

45 It now becomes necessary to reduce the supply of fluid. I accomplish the reduction of the fluid, and thereby control the speed of the wheel, by means of a lever G, connected with

the valve H at one end and at its other end to a baffle or similar device I, which is located in 50 advance of the nozzle and in the path of the spent fluid when the wheel is running above the correct speed, the lever being returned in the other direction by a spiral spring J, connected at one end to the casing and the other 55 end to the lever or the baffle.

In Fig. 1 the baffle I consists of a bucket having a contracted outlet I'. The amount of water which reaches the bucket I will depend on the speed of the wheel, and when the speed 60 passes the desired limit the water in I will be sufficient in quantity to depress the lever G, overcome the power of the spring J, and partially close the nozzle E. The speed of the wheel will then decrease and the water cease 65 entering I, the water which has already entered I will escape through I', and the spring J will raise the lever G and reopen the valve H. The position of the bucket will adjust itself so as to maintain a constant and regulated 70 speed of the wheel.

In Fig. 2 the baffle consists of a troughed metal plate and is rigidly secured to the lever, and the spiral spring is secured to the casing and to the baffle. 75

In Fig. 3 a bucket I, having an outlet I', is suspended from the lever G and the spring J, which is secured to the casing.

In Fig. 4 the baffle I is also a troughed metal plate, and instead of being supported by 80 the lever G and the spring J is pivoted to the casing and connected to the lever, spring J being connected to the baffle and to the casing.

Having thus described my invention, the following is what I claim as new: 85

1. The combination with the casing and a wheel within the casing, of a nozzle delivering fluid tangentially in a line central to the periphery of the wheel, a valve for the nozzle, a lever connected with the valve of the nozzle at one end to reduce or increase the supply through the nozzle, a baffle in alignment with the wheel and the nozzle, connected to the other end of the lever and moved in one direction by the spent fluid, to move the end of 90 the lever thereby reducing the supply through

the nozzle, and a spring connected to the casing and with the baffle to move the said baffle in the other direction to increase the supply.

2. In a speed-governor for water-wheels, turbines and the like, the combination with the casing and the water-wheel, of the nozzle, a lever connected at one end to the nozzle, and a baffle suspended from the other end of the lever, and moving the lever in one direction, 10 and a spring connected with the baffle and the casing and moving the lever in the other direction.

3. In a speed-governor for water-wheels, turbines, and the like, the combination with 15 the nozzle, a baffle consisting of a bucket provided with a contracted outlet, and connec-

tions between the baffle and the nozzle for controlling the supply through the nozzle.

4. In a speed-governor for water-wheels, turbines, and the like, the combination with a 20 nozzle, of a lever secured at one end to the nozzle, a bucket having a contracted opening secured to the other end of the lever, and in the path of the spent fluid, and a spring for returning the bucket and lever to their normal 25 positions.

The foregoing specification signed at Glasgow this 13th day of January, 1903.

JAMES WRIGHT MACFARLANE.

In presence of—

JOHN LIDDLE,

AGNES MACKINTOSH.
